UNITED STATES PATENT OFFICE.

WILLIAM S. GRAFTON, OF STEUBENVILLE, OHIO, AND EDWIN C. EWING AND ALEXANDER GLASS, OF WHEELING, WEST VIRGINIA, ASSIGNEES TO THE WHEELING CORRUGATING COMPANY, OF WHEELING, WEST VIRGINIA.

DESIGN FOR A CEILING-PLATE.

SPECIFICATION forming part of Design No. 22,272, dated March 7, 1893.

Application filed February 4, 1893. Serial No. 461,218. Term of patent 14 years.

To all whom it may concern:

Be it known that we, WILLIAM S. GRAFTON, residing at Steubenville, in the county of Jefferson and State of Ohio, and EDWIN C. EWING and ALEXANDER GLASS, residing at Wheeling, in the county of Ohio and State of West Virginia, citizens of the United States, have invented and produced a new and original Design for Metallic Finishing-Plates for Buildings, of which the following is a specification, reference being had to the accompanying drawing, forming part hereof, which shows a metallic finishing-plate or ceiling-plate designed according to our invention. Our design consists of a square or rectangular metallic finishing plate A, divided by straight, parallel ribs or ridges $a a'$, into rectangular sub-divisions B. The ribs $a a'$ cross each other at right angles, and at each junction of the ribs there is formed a circular

projection b, which is slightly concave, and at the center of the concave projection b, is formed a small convex projection or button c.

The essential feature of our design is a metallic finishing plate having the ribbed projections arranged at right angles to each other and crossing and having the circular projections within which are arranged the convex projections or buttons c.

We claim—

The design for a metallic finishing plate herein shown and described.

In testimony whereof we have hereunto subscribed our names.

WILLIAM S. GRAFTON.
EDWIN C. EWING.
ALEXANDER GLASS.
